(57) **CLAIM**

The ornamental design for a display screen or portion thereof with graphical user interface as shown and described.

DESCRIPTION

The FIGURE is a front view of a display screen or portion thereof with graphical user interface, showing our new design.

The outermost double broken-line rectangle illustrates a display screen or portion thereof and forms no part of the claimed design. The remaining broken lines shown in the FIGURE are environment only and show portions of the display screen or portion thereof with graphical user interface that form no part of the claimed design.
